UNITED STATES PATENT OFFICE.

PAUL S. MOYER, OF CHICAGO, ILLINOIS, ASSIGNOR TO THE ARIDOR COMPANY, OF CHICAGO, ILLINOIS, A CORPORATION OF ILLINOIS.

CONTAINER.

Application filed May 1, 1920, Serial No. 373,079. Renewed April 22, 1925.

My invention relates to containers and particularly to that class wherein it is desirable to protect the contents from the atmosphere and wherein an advantageous and pleasing display of the contents is contemplated, as is the case in containers for hard and dry confections or the like.

Among other objects, my invention is intended to provide a container for so-called "hard candies" et cetera, which, by reason of its general organization and equipment, may serve as an effectual protection and preservative enclosure and may serve, at the same time, as a convenient dispensing jar or holder.

Referring to the drawings, Fig. 1 is a side elevation partly in section of a container illustrating an embodiment of my invention; Fig. 2 is a sectional elevation on the line 2—2 of Fig. 1; Fig. 3 is a sectional elevation on a line 3—3 of Fig. 1; and Fig. 4 is an enlarged detail view illustrating the means for temporarily holding the closure open while dispensing the contents of the container.

In the illustrated embodiment of my invention I have shown a receptacle 4 of any suitable material—preferably transparent and moisture proof—such as glass, provided with a closed end 5 of substantially semi-ellipsoidal form and having its open end terminating in a neck portion 6 having a bead formed on its outer edge and disposed at an angle to the body portion of the container. The lower side of the neck portion occupies a position a substantial distance above the base, thus forming a retaining wall 7 for the contents of the container.

To facilitate the placing of a plurality of these containers side by side and in superimposed tiers without material loss of space, the sides, top and bottom of the container may be flattened as indicated at 8 in Fig. 3. The flattened portion of the bottom is preferably of greater width to provide a substantial base for the container.

A cover or closure 9 is hinged at its upper edge to a band 10 encircling the neck portion 6 between the bead and the body portion of the receptacle and, preferably, is adapted by its own weight, assisted by the spring 11, if desired, to swing downwardly and close the open end of the receptacle.

The cover 9 may be provided on its inner side with an annular rectangular groove 12

into which is secured the opposite edges of a resilient semi-tubular gasket 13, the crown of which extends beyond the inner face of the closure and may be more or less compressed by the bead of the neck portion, thus tending to provide a seal between said closure and receptacle. 60

When a container embodying this invention is used for hard candy or other contents desired to be kept dry, I provide within the container a hygroscopic or absorbent material 14 which tends to decrease the degree of humidity in the container. This material may comprise such a hygroscopic substance as calcium chloride mixed with a body material such as infusorial earth and having a preferably fibrous binder such as asbestos. 65

To retain the hygroscopic material 14 within the container, there is provided a holder 15 having in its side wall adjacent the interior of the receptacle, the perforations 16 to permit of the circulation therethrough of the air in the container. 70

When the hygroscopic material in time has become saturated, it may be removed from the holder and heated or otherwise treated to reduce its moisture content and restore its hygroscopic or absorbent capacity. 80

To secure the holder 15 and its contents removably within the container, I provide a support 17 secured to the closure and having side and lower walls which, with the inwardly projecting marginal flange 18 and the inner face of the closure form a socket 90 having an open upper end into which is placed the holder with its perforated side wall adjacent the interior of the receptacle. Pivotally mounted on the closure above the open end of the support 17 are the clips 19, which when in the position shown in full lines in Fig. 2, will prevent the accidental displacement of the holder and its contents, and when swung to the dotted line position will permit the ready removal of the holder 95 and its contents for the purpose of renovating and replacing the latter. 100

To facilitate the dispensing of the contents, means may be provided for temporarily holding the closure open while the contents are being removed; for example, a resilient member 20 is rigidly secured to the band 10 through the stationary hinge members and has formed at its central portion the downwardly tapered holding lug 21; 110

and the latch or finger 22 secured to and adapted to move bodily with the closure and positioned to cooperate with the lug 21.

In operation, the closure is swung outwardly until the upper cam face of the finger 22 engages the lug 21 when a continuation of the movement of the closure will cause the resilient member 20 to yield and permit the finger to pass to the opposite side of the lug (see Fig. 4) where it will be held by the resilient member and lug assuming their normal position. To release the closure from the holding lug it is only necessary to depress the former until the finger 22 has again passed the lug 21 when the closure will drop into closed position, the gasket 13 acting as a buffer to prevent a severe or destructive impact between the closure and the receptacle.

Obviously the present invention is not limited to the specific embodiment shown and described, and the details of construction and arrangement of the illustrated device may be variously modified without departing from the spirit and scope of my invention. Moreover, it is not indispensable that all of the features of the invention be used conjointly as they may be used to advantage in various combinations and sub-combinations.

Having thus described my invention, I claim:

1. A container comprising, in combination, an elongated horizontally disposed receptacle appropriately flattened in transverse cross-section to adapt it for assembly in a battery or in tiers of like jars; and having a closed tapering portion tending to display the contents of the container distinctively from contents of neighboring like containers in a battery; said receptacle having at its opposite end from the tapered portion a mouth opening obliquely and upwardly; a closure for said mouth and connected thereto to be closed by gravity, and a hygroscopic medium located within the receptacle adjacent its mouth; whereby the bulk of the contents of the receptacle may be located horizontally remote from the mouth thereof and the hygroscopic medium is located in proximity to the contents first affected by admission of moisture at the mouth of the receptacle.

2. A container comprising, in combina-

tion, a horizontally disposed elongated receptacle having an open end; a closure therefor; and means associated with said receptacle, horizontally remote from the bulk of the contents thereof, for controlling the degree of humidity therein.

3. A container comprising, in combination, a horizontally disposed elongated receptacle; a hinged closure therefor; a holder adapted to be removably applied to said closure and open to the circulation of the air in said container; hygroscopic material contained in said holder; and moisture resisting means between said receptacle and said closure.

4. A container comprising, in combination, a horizontally disposed elongated receptacle having an open end disposed at an angle to the body portion thereof and horizontally removed with reference to the closed end of said body portion; a closure therefor; a holder adapted to be applied to said closure and open to the circulation of the air in said container, a dehydrating substance contained in said holder and means for supporting said holder.

5. A container comprising in combination, a horizontally disposed elongated receptacle having an openable end; a closed end horizontally removed therefrom whereby the bulk of the contents of the receptacle may be located horizontally remote from said openable end; a closure for said openable end of the receptacle; and dehydrating means removably connected to said closure and adjacent the contents most affected by admission of moisture to the container.

6. A display receptacle comprising a transparent jar adapted for displaying a mass of contents such for instance as hard candies at a substantial distance from the mouth of the jar, a removable closure for the mouth of the jar, and a hygroscopic medium communicating with and adapted for dehydrating the interior of the jar, said hygroscopic medium arranged proximate the mouth of the jar so as to be adjacent the contents most affected by admission of atmospheric moisture during temporary opening of the jar.

In testimony whereof, I have signed my name to this specification.

PAUL S. MOYER.
